UNITED STATES PATENT OFFICE

2,084,619

FENCE GUARD

Edgar A. Love, Darlington, Ind.

Application July 25, 1936, Serial No. 92,671

1 Claim. (Cl. 256—3)

This invention relates to fence constructions and more particularly to a means adapted to be mounted on a conventional wire fence for preventing cattle or other animals from brushing 5 against the fence.

An object of this invention is to provide a supporting means for supporting barbed wire or the like in outstanding position from a fence so as to keep animals away from the fence and thus 10 prevent the animals from damaging the fence or breaking through the fence.

Another object of this invention is to provide a bracket or supporting means for barbed wire or the like which can be easily mounted on the 15 strands of wire forming a wire fence in order to hold the barbed wire in a horizontal and outstanding position from the fence.

A further object of this invention is to provide a bracket or supporting means which can be constructed out of a relatively rigid rod and which 20 can be readily mounted on the wire fence and can also, when necessary, be removed and mounted on a new or separate fence structure.

A still further object of this invention is to provide a device of this kind which can be applied or 25 removed without the use of tools.

With the foregoing and other objects in view, the invention will be more fully described hereinafter, and will be more particularly pointed out 30 in the claim appended hereto.

In the drawing, wherein like symbols refer to like or corresponding parts throughout the several views,

Figure 1 is a fragmentary top plan of a fence 35 construction having a barbed wire supporting device constructed according to an embodiment of this invention mounted thereon.

Figure 2 is an enlarged sectional view taken on the line 2—2 of Figure 1.

Figure 3 is a perspective view of the barbed wire 40 supporting device.

Figure 4 is a fragmentary sectional view taken on the line 4—4 of Figure 1.

Referring to the drawing, the numeral 10 designates generally a wire fence construction including a plurality of vertical posts 13 having a stranded wire 11 secured thereto by means of staples or other fastening devices 12. This fence structure 10 is a conventional fence structure and 45 is here shown as only one of a number of different types of fence constructions to which the herein-after described invention may be secured.

In order to support one or more strands of barbed wire 14 in outstanding relation to one side 50 of the fence structure 10, I have provided a

bracket or supporting means, generally designated as 15. This barbed wire supporting means 15 comprises a substantially horizontally disposed lower bar 16 and an upper inwardly divergent bar 17, which is integral with the lower bar 16. The lower bar 16 at its outer end is provided with a bent or looped portion 18 and the upper bar 17, has a similar looped extension 19 with the U-shaped extensions 18 and 19 connected together by a reverted looped or U-shaped member 20, forming a support for the barbed wire 14. The U-shaped member 20 preferably has the free legs thereof disposed in outwardly convergent relation as shown in Figure 2, so that it is necessary to pry these free legs apart slightly in order 10 to insert the wire 14 therebetween. This may be done by compressing the two bars 16 and 17 before these bars have been applied to the strands 15 of the fence 10.

The inner end of the lower bar 16 is provided 20 with a U-shaped extension 21, one leg of which is continued by a laterally extending part 22 and this part 22 is then bent rearwardly to provide a holding arm 23 which is adapted to engage on the side of one strand 11 of the fence opposite 25 from the side engaged by the upper leg 24 of the U-shaped member 21.

As shown in Figure 4, the arm 23 is preferably 30 disposed in a plane slightly below the leg 24 so that the strand 11 of the wire will be bent slightly and in this manner the bracket or supporting member 15 will be held against longitudinal movement on the fence. The upper arm or bar 17 has the inner end thereof constructed similar 35 to the inner end of the lower bar 16, being provided with a U-shaped member 25, the lower leg 26 thereof being provided with a lateral extension 27 and this extension 27 has a rearwardly extending arm 28 similar to the arm 23 of the lower leg 16.

In the use of this fence guard and barbed wire 40 supporting means, the bracket or supporting member 15 may, if desired, have the inner ends of the arms 16 and 17 secured to spaced apart strands 11 of the fence 10 and then the barbed wire 14 may be forced between the legs of the U-shaped member 20. In the event the legs of the U-shaped member 20 are spaced apart a distance sufficient to permit the easy removal of the barbed wire 14 therefrom, a tool in the form of pliers or the like may be used to compress the outer ends of the free legs of the member together so that the wire strands 14 cannot be withdrawn 45 therefrom although, if desired, the wire strand 14 might be moved laterally, as where the wire 50

strand 14 is tightened at either end thereof. There may be as many brackets or supporting members 15 as may be desired so as to adequately support the barbed wire 14 in a horizontal position and the relative position of the barbed wire 14 with respect to the ground may be varied at will, depending on the character of animals within the area enclosed by the fence 10.

It is, of course, understood that various changes and modifications may be made in the details of construction and design of the above specifically described embodiment of this invention without departing from the spirit thereof, such changes and modifications being restricted only by the scope of the following claim.

I claim:—

A wire supporting means comprising a V-

shaped member, a pair of reverted U-shaped securing means carried by each divergent end of the member, a free leg of one U-shaped securing means at the divergent ends of the member being disposed in a plane laterally of and parallel to the adjacent leg of said one securing means whereby to bind a wire strand therebetween to thereby frictionally hold said member against longitudinal movement relative to said wire strand, and a U-shaped wire securing means integral with the convergent end of the member, said U-shaped securing means having the free legs thereof directed outwardly of the convergent end of the member.
